Application July 1, 1936, Serial No. 63,598

Term of patent 3½ years

To all whom it may concern:

Be it known that I, Bertha Arkin, a citizen of the United States, residing at New York, in the county of New York and State of New York, have invented a new, original, and ornamental Design for a Shoe, of which the following is a specification, reference being had to the accompanying drawing, forming a part thereof, in which,

Fig. 1 is a plan view of a shoe, showing my new design, and

Fig. 2 is a view of the shoe in side elevation,

the heel being shown conventionally in dot and dash lines.

The dominant feature of the design resides in the triple lines of spaced stitching crossing each other on the tip of the shoe in oblique direction.

I claim:

The ornamental design for a shoe substantially as shown and described.

In testimony whereof, I have affixed my signature hereto.
